ABSTRACT

An ash tray including a supply of liquid such as water that has a ball member floating thereon whereby a cigarette, cigar or the like can be engaged by the moistened ball member to safely and conveniently extinguish the cigarette or cigar.

2 Claims, 5 Drawing Figures

PATENTED JAN 18 1972

3,635,225

ATTORNEY

1
ASH TRAY

The present invention relates to an ashtray, and more particularly to an ashtray that includes a compartment that has a supply of liquid such as water therein, and wherein there is provided a ball-shaped member that floats on the liquid, the ball member being adapted to safely and conveniently extinguish a cigarette or cigar.

An object of the present invention is to provide an ashtray that utilizes a liquid such as water to extinguish a lit article such as a cigarette or cigar, and wherein there is provided a means for conveniently mounting or supporting an ashtray in any desired location such as in an automobile or other vehicle or any other structure.

Another object is to provide an ashtray that includes a liquid compartment and a ball therein, and wherein there is provided a compartment for receiving the extinguished cigarette or cigar butts after the same have been extinguished.

A further object is to provide an ashtray of the type stated that is economical to manufacture and efficient in operation and which is rugged in structure and foolproof in use.

Further objects and advantages are to provide improved elements and improvements thereof of a device that is economical to produce, durable in form and conducive to the most economic use of materials and uniformity of members formed therefrom.

Still further objects and advantages will become apparent in the subsequent description in the specification.

In the drawings:

FIG. 1 is a perspective view of the ashtray of the present invention.

FIG. 2 is a perspective view of the mounting base per se.

FIG. 3 is an enlarged sectional view taken on the line 3—3 of FIG. 1.

FIG. 4 is a sectional view taken on the line 4—4 of FIG. 3.

FIG. 5 is a fragmentary side elevational view on a reduced scale illustrating the ashtray supported on a vertical surface.

Referring in detail to the drawings, the numeral 10 indicates the ashtray of the present invention, and the ashtray 10 includes hollow housing 20 that embodies spaced parallel vertically disposed sidewalls 11, spaced parallel vertically disposed end walls 12 and 13 and horizontally disposed top and bottom walls 14 and 15.

Arranged within the housing 20 is a vertically disposed partition 16 that defines within the housing first and second compartments 17 and 18. The compartment 17 is adapted to hold a quantity of liquid 19 therein and the liquid 19 may be water.

The numeral 21 indicates a closure or lid that is hingedly connected as at 22 to the top wall 14, FIG. 3, and the closure 21 closes an opening 23 in the top of the housing 20. A manually engageable knob or handle 24 is provided for facilitating the opening of the closure 21.

There is further provided an upstanding projection 25 above the compartment 17, and the projection 25 indicates a tapered portion 26 that has a flaring section 29 arranged thereabove, there being a reduced diameter neck 28 between the portions 26 and 29. The numeral 27 indicates a hollow ball that is adapted to float on the liquid 19 in the compartment 17.

Mounted on the lower portion of the housing 20 or formed integral therewith are spaced parallel L-shaped flanges or lugs 30. The numeral 31 indicates a baseplate that is adapted to engage the flanges 30, and a suction cup 32 is secured to the baseplate 31 and depends therefrom. Diametrically opposed lugs 33 may be provided on the baseplate 31 to limit the extent of insertion thereof in the flanges 30.

The end wall 12 is adapted to have a pair of spaced parallel flanges or guide members 34 secured adjacent thereto so that when desired the baseplate 31 can be arranged in engagement with the flanges 34 in order to permit the ashtray to be mounted on a vertical surface as the surface 35, as shown in FIG. 5.

From the foregoing, it will be seen that there has been provided an ashtray that utilizes a supply of liquid in conjunction

2

with a ball member to safely and conveniently extinguish cigarettes, cigars and the like. In use with the parts arranged as shown in the drawings, the ashtray 20 can be mounted in a suitable location such as the dash of an automobile or other vehicle such by arranging the suction cup 32 to engage the horizontal supporting surface. It is to be understood that the ashtray of the present invention can be used in any desired location, and its use is not restricted to use in a vehicle. With the suction cup 32 engaging the supporting surface the mounting place or surface engages the flanges 30 so that the housing 20 can be conveniently supported in a desired location. The compartment 17 is adapted to be filled or supplied with a suitable liquid such as water or other suitable liquid 19. Thus, when a cigarette or cigar is to be extinguished the user need only insert it down through the flaring portion 29 of the tapered portion 26 to cause the cigarette to engage the ball 27 whereby the water will safely extinguish the cigarette. After the cigarette or cigar has been extinguished, the knob 24 can be manually gripped so that the closure 21 can be swung open from the solid line position of FIG. 3 to the broken line position of FIG. 3 so that the butts can be conveniently dropped in the compartment 18. The closure 21 can be returned to its closed position relative to the opening 23.

The ball member 27 is of a hollow construction so that if it floats on the upper surface of the liquid 19 whereby the ball member 27 will coat with the reduced diameter neck 28 of the projection 25 that prevents the liquid 19 from sloshing out through the projection 25 as for example when a vehicle is moving or the like. In addition, the ball member 27 is free to rotate or move in the compartment 17 so that its outer periphery or surface will be wetted by the water or other liquid 19 to bring about the desired extinguishing action as previously stated.

The mounting plate 31 has the ears or lugs 33 thereon which will help limit movement of the parts 20 and 31 relative to each other so that they will not accidentally separate in the wrong direction. When it is desired to empty the container 18 the entire housing 20 can be separated from the mounting plate 31 if desired so that the closure 21 can be opened and the device can be turned upside down to discharge the extinguished cigarette butts from the compartment 18. Thus, the device can be used over and over again. Thus, when desired additional quantities of liquid 19 can be placed in the compartment 17 by filling the compartment 17 through the projection 25.

As shown in FIG. 5, the device can also be mounted contiguous to a vertical surface 35 due to the provision of the flanges 34 on the end wall 12 of the ashtray. In FIG. 5 the suction cup 32 conveniently engages a vertical wall surface 35, and the mounting plate 31 engages the flanges 34 whereby the device can be conveniently supported in this manner.

The parts can be made of any suitable material and in different shapes and sizes.

It will, therefore, be seen that there has been provided a liquid-extinguishing ashtray that uses water or any other suitable liquid. The device can be conveniently used in automobiles, airplanes, boats and the like.

Other mounting means can be used besides those shown or described. For example, clips or holders can be used or an adhesive type of arrangement can be used or a hook arrangement can be used. The ball member 27 can be made of a suitable material that will float but will not burn. In addition, since the ball can turn freely the outer surface of the ball will be moistened to assert the desired extinguishing action.

The ball 27 may have any desired or suitable construction, for example, the ball 27 may have a smooth or plain surface or it may be roughened. In addition, the ball may be impregnated or otherwise provided with a luminescent or fluorescent material so that it will glow in the dark.

While a preferred embodiment in accordance with the present invention has been illustrated and described, it is understood that various modifications may be resorted to without departing from the spirit and the scope of the appended claims.

What is claimed is:

1. An ashtray comprising a hollow housing including vertically disposed spaced parallel sidewalls, vertically disposed spaced end walls, horizontally disposed top and bottom walls, a vertically disposed partition arranged in said housing defining first and second compartments, said first compartment having a quantity of liquid therein, a closure hingedly mounted upon said first compartment, a projection above said first compartment, and said projection including a tapered

portion terminating in a reduced diameter neck, there being a flaring section positioned above said neck, a ball floating on the liquid in the first compartment, spaced-apart flanges affixed to said housing, a baseplate for selectively slidably engaging said flanges, and a suction device secured to said baseplate.

5 2. The structure as defined in claim 1, wherein said ball has a plain surface.
